United States Patent Office.

J. H. WHEELER, OF ADDISON, VERMONT.

Letters Patent No. 73,855, dated January 28, 1868.

IMPROVEMENT IN MATCH-BOXES.

The Schedule referred to in these Letters Patent and making part of the same.

TO ALL WHOM IT MAY CONCERN:

Be it known that I, J. H. WHEELER, of Addison, in the county of Addison, and State of Vermont, have invented a new and improved Match-Box; and I do hereby declare that the following is a full, clear, and exact description thereof, which will enable those skilled in the art to make and use the same, reference being had to the accompanying drawings, forming part of this specification.

This invention relates to a new and useful improvement in match-boxes, whereby they are rendered much more convenient than those in ordinary use; and it consists in such an arrangement of slides and springs that the box is not only made to contain the matches for pocket or other use, but provision is made for igniting the same, and holding them for use when lighted, as will be hereinafter described.

This match-box is made to contain any given and convenient number of matches, which are arranged therein with their prepared ends all in one direction, and the box is so constructed that a single match may be taken and separated from the rest, and shoved upward through the end of the box, where it is ignited by a slide, and afterwards held by the slide until used.

Figure 1 represents a side view of the box, showing the springs which actuate the pin within the box, by which a single match is separated from the rest.

Figure 2 is a view of the opposite side of the box, showing the slide which holds the cap-slide in place when the box is not in use.

Both of these views represent the box closed as when carried in the pocket.

Figure 3 is a section of fig. 1, through the line *x* *x*, giving an edge view, and showing the separating-pin.

Figure 4 is a section of fig. 3, through the line *y* *y*, showing the box split in two parts, with matches therein, shown in red, with one match separated from the rest and ignited.

Similar letters of reference indicate corresponding parts.

A is the box. At the base of the box there is a slide, *a*, which, when withdrawn, allows the matches to be introduced into the box. *b* is a stud, by which the slide *a* is operated; *c* represents a spring on the outside of the box, and *c'* is a lever attached thereto, which is pushed in by the stud *d*. The fulcrum of the lever is at *e*. *f* is a pin, which is thrown out and in by pressing on the stud *d*; *g* is a slide on the edge of the box, which is operated by the finger bearing against the stud *h*. By this slide the match is shoved through the orifice in the end of the box, as seen at *i*. *J* is the cap of the box, which slides in grooves, as seen in fig. 3; *m* is a slot in the side of the slide, and *n* is a stop-pin by which the slide is controlled in its motion back and forth; *o* (fig. 2) is a slide which fastens the cap *J* when it is pressed down, as seen in the drawing. The under side of the slide *J* is roughened something like a file, for producing the necessary friction on the match when it slides in contact with it.

The operation will be readily understood from the drawing. After the matches are placed in the box the pin *f* is withdrawn by pressing on the stud *d*, and the box is turned so that the matches will fall upon that side of the box. The pressure on the stud *d* is now removed, when the pin *f* will separate one match from the rest, and hold it while the slide *g* is brought up, when the end of the match is shoved against slide *J*, which slide is drawn back with a quick movement, which ignites the match, as seen in the drawing. After ignition the match is shoved up through the aperture *i* by the slide *g*, where it may be held for use by pushing back the slide *J* against it. When used, the match is withdrawn, and the slide *J* is replaced, as seen in fig. 2, and the box is ready for another operation.

Having thus described my invention, I claim as new, and desire to secure by Letters Patent—

The combination, with the box *A*, of the sliding cap *J*, slides *a* *g*, separator *f* *c* *c'*, and slide-lock *o*, all constructed, arranged, and operating substantially as set forth, and for the purpose specified.
